UNITED STATES PATENT OFFICE.

ALBERT CONLEY, OF PEYTONA, WEST VIRGINIA.

BOOK-CLASP.

No. 922,858.

Specification of Letters Patent.

Patented May 25, 1909.

Application filed June 5, 1907. Serial No. 377,407.

To all whom it may concern:

Be it known that I, ALBERT CONLEY, a citizen of the United States, residing at Peytona, in the county of Boone, State of West Virginia, have invented certain new and useful Improvements in Book-Clasps; and I do hereby declare the following to be a full, clear, and exact description of the invention, such as will enable others skilled in the art 10 to which it appertains to make and use the same.

This invention has relation to pen and pencil holders that are adapted to be attached to means for holding account books and similar 15 articles in closed position.

It is the object of the invention to provide an exceedingly cheap and simple device, whereby a pencil holder and other needed devices may be connected with a plate to the 20 ends of which an elastic band is secured to hold an account book in closed position, so that bills and other loose papers may be held in the book, and so also that a pencil and other devices needed in connection with carrying on the work or recording receipts or 25 charges or taking census records and similar matters, may be held in the book or in readiness for use.

The nature of the invention is fully and 30 clearly ascertainable from the device portrayed in the annexed drawing, forming a part of this specification, in view of which it will first be described with respect to its construction and mode of use, and then be 35 pointed out in the subjoined claim.

The drawing is a perspective view of the pencil holder, showing it as applied to a day-book, the latter being represented in dotted lines.

40 In the drawings, A designates a bar of sheet metal, having an open clamp, 4, secured transversely on its outer side by rivets, or other suitable means.

The clamp will be made of spring metal, so 45 that a pencil may be placed in the clamp and be held in place therein; and when the pencil

is wanted for use it can be pulled out of place by merely lifting it upward or outward or pulling it endwise out of its clamp.

The bar A is provided with holes at its 50 ends by which to rivet or secure thereto the ends of an elastic strip or band, 3, of suitable construction, so that it may be stretched around an account or day-book, or the like, to hold the latter in closed position and retain in place any loose papers such as bills, receipts and the like, that may be inclosed therein.

The rubber or elastic strip or band 3 may be as stout or large as may be desired, and in 60 case it should break in use, it can be replaced by a new one at a trivial cost. The means for attaching the band to the strip may be other than rivets so long as they perform 65 their proper functions.

It will be noticed that the pencil holder comprises an open-seam tube which has its seam edges slightly flared outward.

The metal plate A is adapted to have other devices secured to it, for instance, a pencil 70 sharpener, 7, and a case 8 for holding a rubber eraser, or any other desired article or articles.

It is of course understood that when detached from the book, the rubber band 3 75 lies flush against the bar A.

What is claimed is—

The combination with a book, of a rigid bar corresponding in length to the width of the book and bearing thereon, and a band of 80 elastic material connected at its ends to the ends of the rigid bar and extending around the book, whereby the rigid bar is connected yieldably to the book and protects the edges thereof from abrasion by the band. 85

In testimony whereof, I affix my signature, in presence of two witnesses.

ALBERT CONLEY.
